UNITED STATES PATENT OFFICE

GORDON A. BURR, OF WILKINSBURG, PENNSYLVANIA, ASSIGNOR TO WESTINGHOUSE ELECTRIC & MANUFACTURING COMPANY, A CORPORATION OF PENNSYLVANIA

CONDENSER BUSHING

Application filed January 10, 1929. Serial No. 331,583.

My invention relates to electrical bushing structures and particularly to bushings of the condenser type.

One object of my invention is to provide a bushing, of the above-indicated character, in which the power loss, in the form of heat therein, as compared to similar bushings heretofore employed, shall be greatly reduced.

10 Another object of my invention is to materially reduce the quantity and weight of material required for condenser bushings of given voltages.

Another object of my invention is to provide a condenser structure that shall employ a slightly porous but relatively dense dielectric-layer material and a binder therefor that shall not penetrate the layer surface beyond a certain depth.

20 A further object of my invention is to provide a condenser or bushing structure that shall be simple and durable in construction, economical to manufacture and effective in its operation.

25 Heretofore, it has been customary, in high-voltage bushing practice, to construct a bushing of alternate relatively thin conducting and dielectric layers or cylinders of successively greater diameters and lesser lengths 30 to provide nearly uniform capacity between the conducting layers and to impose substantially uniform stress on the dielectric layers.

35 However, for relatively high voltages, the number of layers in, and the radius of, the bushing become so great that, under alternating high-voltage stresses, there is a considerable power loss, in the form of heat. This loss has been a troublesome problem and a material limitation as to the kinds of apparatus and the values of voltage that could be 40 safely, economically and commercially employed.

45 This heat-power loss, under alternating high-voltage stresses, apparently occurs in all solid and fluid dielectric materials and, since the solid material cannot dissipate its heat by convection, the heat must be conducted to the surface and radiated.

It is therefore, important and necessary, if 50 condensers similar to that of my invention are

to be rendered more effective and adapted for high-voltage service, that the dielectric losses shall be reduced and the dielectric strength increased.

Condenser bushings have been improved from time to time by taking advantage of advanced manufacturing methods, employing the best materials that could be found to suit the purpose, making mathematical and scientific computations beforehand and by ingenious changes of structure.

My invention however, is a discovery which, while apparently contrary to the best thought and practice in this field, has resulted in a structure of such marked improvement in performance, over prior-art structures, as to be almost unbelievable to those skilled in this field.

In the past, the preferred dielectric, over which no improvement has been made or suggested, so far as I am aware, has consisted of a porous paper treated with a binder, such as shellac or similar resinous material. Further treatment of the shellacked paper, under heat and pressure, caused the shellac to penetrate entirely through the paper and apparently left no voids or gas pockets therein.

All theory and laboratory tests of those most interested and best versed in this art indicated that the above porous paper and its treatment to eliminate voids and gas pockets was the most effective method of obtaining low dielectric losses and high dielectric strength and was essential to the production of a bushing having the desired dielectric properties.

In accordance with my discovery, the above-mentioned voids and gas pockets apparently do not have any adverse effect, provided they are sufficiently minute and evenly distributed.

Instead, therefore, of employing a highly porous paper having pronounced voids and gas pockets and being subject to complete, or nearly complete, penetration by the shellac, I employ a relatively dense paper which, while sufficiently porous to securely grip the binding material, is not penetrated thereby to any great depth. In other words, while the binder or shellac may penetrate the dielectric

100

to a sufficient depth to obtain an effective bond therewith, there is a stratum or layer, intermediate the opposite surfaces, of the dielectric layer, that is free of the binder.

5 Contrary to the usual expectations that voids and gas pockets would adversely affect the structure, it has been found that, in a bushing constructed in accordance with my invention, the internal loss per unit volume 10 is reduced to approximately one fifth the value obtained by the former structure.

15 This very surprising result permits a higher electrostatic stress to be safely employed, reduces the radius of the bushing and the quantity of dielectric material in a condenser for a given voltage service, lowers the cost of manufacture and transportation charges, saves storage and operating space, 20 permits desirable improvements in co-operating apparatus and has other advantages, such as reduction of labor and facility of handling.

25 Figure 1 of the accompanying drawing, is a side view, partially in elevation and partially in section, of a condenser bushing embodying my invention.

30 Fig. 2 is an enlarged detail sectional view of a portion of the structure, as viewed at the upper right-hand portion of Fig. 1, and

35 Figs. 3 and 4 are similar cross-sectional views, on a greatly magnified scale, of fragments of the paper formerly employed and that employed in my invention, respectively, illustrating in a diagrammatic way, the relative densities and degrees of penetration by the binder.

40 The device comprises, in general, a central through conductor 2 and a plurality of alternate conducting and dielectric cylinders or layers 3 and 4, respectively.

45 The layers 3 and 4 are of successively outwardly greater diameters and lesser lengths to provide nearly equal capacities or any desired grading of capacities between the conducting layers 3.

50 This arrangement results in a structure, as shown in Fig. 1, having an intermediate cylindrical body portion 6 and tapered or stepped end portions 7 and 8, respectively.

55 The intermediate portion 6 is for mounting the bushing in an opening in a tank cover and the end portions 7 and 8 may be of any desired relative lengths in accordance with the service for which they are adapted and of the medium in which they are to operate.

60 The conducting layers may be of any suitable material, such as lead or tinfoil, but are preferably of embossed aluminum foil having one or both surfaces treated or coated with a binder, such as shellac.

65 The dielectric layers 4, although illustrated in Figs. 1 and 2 for clearness as comprising a single thickness of solid dielectric material, are each preferably wound of sev-

eral layers of paper, each layer being provided on one or both sides thereof with a binder similar to that on the conducting layers 3.

70 The layers 3 and 4 are preferably prepared in advance, as above described, with the shellacked surfaces applied thereto and dried.

75 These layers are then wound under heat and pressure, causing the shellac to momentarily soften and to permanently harden, whereby the conducting and dielectric layers 3 and 4 are securely bonded to each other.

80 Fig. 3 illustrates an edge view of the porous paper heretofore employed, magnified many times, since it is actually relatively thin, being of a thickness of approximately three and one half to five mils.

85 This paper, under the above described process of shellacking and winding, under heat and pressure, becomes thoroughly penetrated or impregnated with the shellac, as indicated by the stippling in Fig. 3.

90 Fig. 4 is a similar view of the more dense paper which does not permit the shellac to penetrate it very deeply, as indicated by the stippling. However, the penetration or adherence is sufficient to provide a bond between the several layers thereof and between the paper and the foil that is as effective as in the prior practice.

95 This paper is preferably of such density, in a sheet of substantially 5 mils thickness and one square inch area, that it requires one hundred and thirty-five seconds, or a greater time, to pass one hundred cubic centimeters of air therethrough under a constant pressure of approximately twenty ounces avoirdupois.

100 This density of paper insures that the paper will remain free of the resin, as to its interior pores, and, as above stated, effects the surprising result of reducing the dielectric loss to about twenty per cent or less of that existing in the penetrable or porous paper previously employed.

105 As an example of the results attained from this construction, a bushing for 220,000-volt service may be constructed at a saving of approximately one-third its former quantity of material, and it is estimated that a bushing for 330,000-volt service may be constructed as a standard commercial structure at a saving of one-half the quantity of material, with other attendant economies and advantages. These results are premised upon 110 actual test and performance of bushings now being commercially used to supersede those of the former type.

115 While I have shown and described a particular form of my invention, changes may be effected therein without departing from the spirit and scope thereof, as set forth in the appended claims.

120 I claim as my invention:

1. A condenser including a conducting

- layer, a flexible dielectric layer and a binder between the layers, the binder penetrating the dielectric layer but only to a sufficient depth to be effectively secured thereto.
- 5 2. A condenser including a conducting layer, a fibrous dielectric layer and a binder between the layers, the dielectric layer having a stratum intermediate its surfaces substantially free of the binding material.
- 10 3. A condenser including a conducting layer, a fibrous dielectric layer and a binder between the layers that only slightly penetrates the dielectric layer.
- 15 4. A condenser including a conducting layer, a paper dielectric layer and a binder therebetween, a space between the surfaces of the paper being substantially free of penetration by the binder.
- 20 5. A condenser including alternate flexible layers of conducting and dielectric materials held together by a binder which penetrates the dielectric material only to a relatively slight depth relative to the thickness thereof.
- 25 6. A condenser including a conducting layer and a dielectric layer of flexible material having a porosity corresponding to a porosity, in a sheet of the material of approximately five mils thickness and one square inch area, requiring more than one hundred and thirty-five seconds to pass one hundred cubic centimeters of air under a constant pressure of approximately twenty ounces avoirdupois therethrough.
- 30 7. A condenser bushing including concentric alternate layers of conducting and dielectric materials, the latter consisting of paper having a porosity corresponding to a porosity, in a sheet of the material of approximately five mils thickness and one square inch area, requiring more than one hundred and thirty-five seconds to pass one hundred cubic centimeters of air under a constant pressure of approximately twenty ounces avoirdupois therethrough.
- 35 8. A condenser including a conducting layer, a paper dielectric layer and a layer of shellac between said layers that penetrates the paper layer by less than one-half the distance therethrough.
- 40 9. A condenser bushing including concentric alternate layers of conducting and dielectric materials, the latter consisting of paper having a porosity corresponding to a porosity, in a sheet of the material of approximately five mils thickness and one square inch area, requiring more than one hundred and thirty-five seconds to pass one hundred cubic centimeters of air under a constant pressure of approximately twenty ounces avoirdupois therethrough, and a binder for holding the layers together which penetrates the paper but only to a sufficient extent to hold the paper to the conducting material.
- 45 10. A condenser bushing including concentric alternate layers of conducting and dielectric materials, the latter consisting of paper having a porosity corresponding to a porosity, in a sheet of the material of approximately five mils thickness and one square inch area, requiring more than one hundred and thirty-five seconds to pass one hundred cubic centimeters of air under a constant pressure of approximately twenty ounces avoirdupois.
- 50 11. A condenser including a conducting layer and a dielectric layer having a stratum parallel to, and between, its surfaces solely of paper.
- 55 12. A condenser including a conducting layer and a dielectric layer embodying a stratum parallel to, and between, its surfaces, solely of paper, the voids in which are of substantially uniform size and distribution throughout.
- 60 In testimony whereof, I have hereunto subscribed my name this 8th day of January, 1929.
